CLEANING IMPLEMENT FOR BARBEQUE GRILLES

William Bruce Delamater, 9114 Valley View,
Whittier, Calif. 90603

Filed May 30, 1972, Ser. No. 258,218

Term of patent 14 years

Int. Cl. D7—05

U.S. Cl. D7—184

FIG. 1.

FIG. 2.

FIG. 3.

FIG. 1 is a perspective view, looking from the head of the cleaning implement for barbecue grilles, toward the handle, showing my new design;

FIG. 2 is a perspective view thereof, looking from the handle toward the head; and,

FIG. 3 is a plan view of the head thereof.

I claim:

The ornamental design for cleaning implement for barbecue grilles, substantially as shown.
